UNITED STATES PATENT OFFICE.

LELAND S. ROSENER AND DAVID H. PATTERSON, JR., OF SAN FRANCISCO, CALIFORNIA,
ASSIGNORS TO THE PARAFFINE COMPANIES, INC., OF SAN FRANCISCO, CALIFORNIA, A CORPORATION OF DELAWARE.

PAPER-MANUFACTURING SYSTEM.

Application filed July 28, 1924. Serial No. 728,600.

This invention relates to a plant for the manufacture of paper, and especially to the mechanism and its control that supplies the raw material to the beater mills, where the material is mixed to a pulp. 5 be shut down, and production of paper is at 55 a standstill until the repairs are made. Since the beaters represent a large investment of funds, it is apparent that it is inefficient to leave them idle for large periods of time.

In the manufacture of cardboard or the like, the raw material utilized must be supplied to beaters or mills, where it is mixed with the proper amount of water to form a 10 pulp of the proper consistency, which is supplied to the paper making machines proper. For a small plant, utilizing only a few beaters, all of the apparatus may be accommodated in a comparatively small space, and 15 no great difficulty is experienced in tending the machinery so as to keep the beaters properly supplied with raw material. However, where a large number of beater mills are used, such as a dozen or so, perhaps each requiring 20 special material, the coordination of all of the various mechanisms in such a way as to keep the plant running smoothly and economically, is a difficult problem. It is one of the objects of our invention to make it possible 25 to operate such a large plant with ease, and to supply the beaters rapidly with material as required. 70

In the manufacture of such paper that is usually designated as "board" or "paste-board", it is not essential to choose with a 30 high degree of care the kind of raw material supplied to the beaters. Therefore, such waste matter as rags, telephone directories, or waste rolls of paper, could be used. But in 35 the past, it has been inefficient to supply such material to the beaters, although available in large quantities, because they are too bulky, and if dropped into the beaters, would cause frequent breakdowns and other effects 40 necessitating wasteful delays. 85

That these effects are quite likely to happen may readily be appreciated when the character of the beaters is understood. These beaters each comprise a wheel having numerous radial extensions called beater bars, revolving in a tank supplied with water. These beater bars are adapted to beat the material to a pulp as such material passes between them and a stationary platform. If it 45 is attempted to operate the beater on such bulky objects as referred to heretofore, the wear and tear on the beater bars destroys them quite rapidly. When such bars are in need of replacement, the entire beater must 50 be shut down, and production of paper is at 55 a standstill until the repairs are made. Since the beaters represent a large investment of funds, it is apparent that it is inefficient to leave them idle for large periods of time. 60

It is another object of our invention to make it possible to use such bulky material for the manufacture of paper, while the hard usage on the beaters is obviated. This we secure by providing an extra step in the process of manufacture, whereby the raw material is 65 first shredded into comparatively fine particles before it is fed to the beaters. The shredders that perform this function are easily kept in repair, and are in general more rugged than the beaters. 70

In addition to the advantages already enumerated, the provision of the shredders makes it possible to speed up the beating operation, since the raw material is supplied to it in a finely divided state. The tendency of 75 the beaters to become clogged by "plugs" is also overcome for the same reason. These "plugs" are caused by the matting together of the material at the intake side of the beater, and their formation is entirely avoided by the use of material which had previously been passed through the shredding operation. This advantage results even where the raw material is not so bulky but that it could be directly placed in the beater. 80

It is still another object of our invention to make it possible to produce a uniform grade of product, by careful weighing of the raw material that is supplied to the beaters. 85

In large paper making systems, such as referred to, we prefer to centralize the control of substantially all of the machinery at one point, so that one attendant is capable of setting any of them into operation by the use of remote control devices, such as electrical or 90 pneumatic control circuits. It is another object of our invention to render such a control system highly satisfactory, as by the aid of signaling devices, serving to apprise the attendant not only of the requirement for supplying certain beaters with raw material, but also of the movements of the mechanisms and cranes controlled by him. 95

It is still another object of our invention to provide such a signaling system that is reliable in operation. 100

It is still another object of our invention to provide improved machinery for the plant, 105

so that better results may be obtained, and the work accomplished in faster time.

It is still another object of our invention to provide a distributor for supplying any 5 of the beaters with raw material that is simple in construction and efficient in operation.

Our invention possesses other advantageous features, some of which, with the foregoing, will be set forth at length in the following 10 description, where we shall outline in full that form of our invention which we have selected for illustration in the drawings accompanying and forming part of the present specification. Although we have 15 shown in the drawings but one embodiment of our invention, we do not desire to be limited thereto, since the invention as expressed in the claims may be embodied in other forms also.

20 Referring to the drawings:

Figure 1 is a plan view of one part of a paper manufacturing plant; this part in the present instance being housed in a separate building and including the shredders and 25 scales;

Fig. 2 is a longitudinal sectional view of the building shown in Fig. 1, with the various machinery shown more or less diagrammatically;

30 Fig. 3 is a plan view of the remainder of the installation, shown diagrammatically and as housed in a separate building; this building houses the beaters (only a few of which are shown, to reduce the size of the 35 figure), as well as the distributing devices for supplying the beaters;

Fig. 4 is a fragmentary elevation of one end of the crane that forms an element in the distributing system, as well as of the contacts that are operated thereby for controlling 40 other elements of the system;

Fig. 5 is an elevation of the control board that centralizes the operation at one point;

Fig. 6 is a side elevation of a signaling device used by an attendant in the beater room to apprise the central control board operator which beater is to be supplied with material;

Fig. 7 is a cross-sectional view of the device shown in Fig. 6;

50 Fig. 8 is a fragmentary longitudinal section through the device shown in Fig. 6; and

Figs. 9, 10 and 11 are separated portions of a complete wiring diagram of the centralized 55 control for the operation of the plant.

In the building, the walls of which are indicated at 20 in Figs. 1 and 2, is located the central control panel 21. This panel is supported on an appropriate platform 22, between a pair of scales 23 and 24. The description is most appropriately started with these scales, since it is here that the reception of the raw material for the entire plant takes place. The first step is the measurement of 65 that material at either of the scales 23 and

24 (or at both when necessary), this material being dumped thereon as from chutes or the like. The scales 23 and 24 have dials 25 and 26 which indicate to the central control operator what the weight is on each scale. When a sufficient amount of raw material is deposited on the scale, a mechanism is provided for moving the charge toward the shredder. This charge of raw material may include such things as telephone directories, 75 waste rolls of paper, cardboard, bales of rags, etc., and it is the function of the shredders to subdivide this raw material into very small pieces, so as to make it suitable for use in the beaters or pulp mills. Were it not for 80 this shredding operation, these bulky objects could not be efficiently treated in the beaters.

The mechanism for moving the charge off the scales 23 and 24 includes the scale conveyor belts 27 and 28, which are endless and disposed over the scale platforms. The charge is of course dumped on these conveyors, which after the charge is weighed, are driven as by the reversible electric motors 29 and 30 to carry the charge to either of the conveyors 31 and 32. In order that either of the scale conveyors 27 and 28 may be used indiscriminately to carry the material to either of the conveyors 31 and 32, these 90 conveyors are placed parallel to each other, and the scales 23 and 24 are located between them. In this way, by operating motors 29 and 30 in the proper direction, it is possible to drive the conveyors 27 and 28 either to 100 carry the material to the conveyor 31 or to the conveyor 32.

The conveyors 31 and 32 travel toward the right, and finally discharge their load to the feeder belts 33 and 34, which are shown as 105 inclined slightly toward the direction of travel. The drive for conveyor 31 and its associated feeder 33 is effected by the aid of an electric motor 35, serving to drive conveyor 31 which is mechanically connected to 110 feeder 33 as by the gearing 37. A motor 36, similar to motor 35, serves analogously to drive the conveyor 32 and feeder 34, these two mechanisms being geared together as indicated at 38. Stationary sides 39, 40 are 115 provided between which the conveyors and feeders run, in order to form deep troughs or channels for the raw material, with the moving belts forming the bottoms of the channels. The feeders 33 and 34 finally discharge their load into hoppers 41 and 42 which lead to shredders 43 and 44. However, in order to keep the flow of material to the shredders more or less uniform, we provide "kickers" 45 and 46 for each feeder, for beating down this material to a comparatively low level, and to prevent the piling up of material at the shredder hoppers. These kickers are mechanically driven in any appropriate manner from the feeders 33 and 120 125 130

34, and comprise a wheel having radial spokes similar to paddles for operating on the raw material.

The shredders 43 and 44 are each driven by powerful electric motors 47 and 48, at a very high speed. The intake side of each shredder communicates with the bottom of the hopper 41 or 42; these shredders are shown only diagrammatically in Figs. 1 and 2, and each comprises a heavy wheel with pivoted radial arms which are adapted to pass between stationary blades. The force of these shredder arms, due to their weight and velocity, is sufficient to tear up the raw material into small bits, even when that material includes large rolls of defective paper which have been scrapped, and heavy books such as telephone directories and the like. Of course under such circumstances the load on the motors 47 and 48 fluctuates considerably, and for this reason it is advisable to utilize rugged and rather powerful motors—such as squirrel cage induction motors.

The shredders 43 and 44 are each encased in sheet metal; the casings 49 and 50 however communicate at the intake end with the hoppers 41 and 42, and at the discharge end of the shredders with the blowers 51 and 52. These blowers suck in the shredded material and blow it through pipes 53 and 54, and into the building where the beaters are located. These blowers are operated by the motors 55 and 56, and thus serve as one link in the chain of mechanism for transporting the material from the shredders.

In Figs. 1 and 2, we have shown the general character of the building which may be used to house the apparatus as thus far described. Thus the conveyors, feeders, shredders and blowers are shown as located in a basement, above which extends the flooring 55. In the flooring, spaces may be provided, guarded by railings 56, to permit inspection of the machinery from the floor. Likewise stairways such as 57 are provided for permitting ready access to the basement whenever it is necessary for a more careful inspection, renewal or repairs. It is also to be noted that as thus far described the apparatus is in duplicate, and we arrange the controls therefor in such a way that either or both may be run at any time, as rendered necessary by the requirements of the beaters or pulp mills.

The beater room is shown in plan in Fig. 3, with three beaters or mills 58, 59 and 60. However, as indicated by the break through the building, many more beaters may in fact be provided. In the present instance twelve such beaters are provided for in the control, divided into two units of six each. These beaters 58, 59, 60, etc., are driven continuously from any source of power; they comprise vertical tanks in which a properly constructed rotor 61 is disposed to serve as a mixer. It is also arranged to supply water to any tank

as desired. Included in the tank is a separating screen 62 which permits only the finely divided pulp to pass downwardly into the suction pipe 63, and thence to the calender rolls or the like for manufacturing the paper or cardboard. Larger pieces, incapable of fine comminution or subdivision, such as wire or leather coming in from the shredders, are prevented by the screen from entering the pulp supply pipes 63, and gradually settle to the bottom whence they may be later removed.

The pipes 53 and 54, which extend upwardly from the discharge end of blowers 51 and 52, finally lead into cyclones 64 and 65 which serve to permit the finely divided raw material to settle gently on a shuttle conveyor belt 66. This belt, as shown most clearly in Fig. 4, is looped over the end pulleys 67, and is concaved by the aid of the guide rollers 68, which have axes making a slight angle with the horizontal. The upper reach of the conveyor 66 is disposed between relatively stationary side plates 69 which form a channel or guide of which the belt 66 forms a moving bottom. Appropriate structural framework 70 serves as the support for the guide pulleys and their bearings, as well as for the sides 69. Furthermore, the lower reach of the conveyor 66 is guided against lateral movement by a plurality of vertical guide pulleys, such as shown at 71 in Fig. 4, and is also guided against undue looseness by the horizontal rollers 72. The belt is arranged to be driven by a drive motor 73 which is geared to the left hand roller 67. This motor is reversible, so that the conveyor belt 66 may discharge its load either to the right hand hopper or chute 74 or to the left hand hopper or chute 75.

The entire conveyor 66 and its support is arranged to be bodily moved transversely of the beaters 58, 59, 60, etc., so as to make it possible to position one of the two hoppers 74, 75 with any one of the beater tanks. For this purpose, it is evident that this "shuttle" travel need be only provided for approximately half of the lateral distance occupied by the beaters; since the right hand hopper 74 is used to discharge material to any one of the right hand beaters, while the left hand hopper 75 is used to discharge material to any one of the left hand beaters. In Fig. 3 which is, after all, mainly diagrammatic, the shuttle conveyor 66 is shown as extended to almost the full length of the building, but this is done in order to permit illustration of the driving motor 73 and of left hand hopper 75, which elements would be otherwise left off due to the break in the building. To this extent there is a departure from exactitude in the drawings. The conveyor 66 is of course moved by this motor 73 in the proper direction to discharge to the desired beater after the shuttle travel has been adjusted to bring one or the other of the spouts or hoppers 74

and 75 over the desired beater tanks. In order to provide for this shuttle movement of the conveyor 66, the entire conveyor as well as its associated chutes or hoppers 74 and 75, 5 is hung on a plurality of pulleys 76 (Fig. 4) which engage the lower flanges of one or more heavy I-beams 77 supported appropriately in the building 78. In order to move the conveyor 66 back and forth along the 10 I-beams, and thus impart to it the shuttle-like movement, we provide a winch 79, on which a cable 80 is wound. This cable is fastened at its opposite ends to corresponding opposite sides of the conveyor supporting frame 15 70, and is guided for this purpose by the guide pulleys 81. A reversible motor 82 serves to drive the winch 79 in either direction, and thereby to exert a pulling force through cable 80 either at the right or left 20 hand end of the conveyor structure 70.

The driving motor 73 for the conveyor 66 is of course arranged on this structure, and connections thereto are provided by the aid of a plurality of trolley wheels 83. These 25 wheels are pivoted in the end of levers 84, supported on the structure 70, and appropriately insulated as by the insulator 85. The levers 84 are counterweighted as by the weights 86, whereby the wheels 83 are resiliently urged against the tracks provided for them. Additional tracks are also provided to produce indications at the control panel 21, of the position of the shuttle conveyor. Thus tracks 87, 88 and 89 may be used to 30 provide the motor connections, while the other tracks 90, 91 and 92 may be used to operate the indicating mechanism. It is further to be noted that these tracks 87 to 92 occupy relatively short distances along the 40 line of travel of the conveyor 66, the remaining gaps being filled by insulation bars 93 which serve to prevent the trolley wheels 83 from running off the tracks. These tracks as well as the bars 93 are appropriately suspended, as by the aid of insulators 94, clips or ears 95, and extensions 96, from suspensions 97, which in turn are fastened by the aid of angle irons 98 to the vertical flange of the I-beam 77. Of course the particular mode 50 of suspension may readily be varied to suit particular conditions.

By referring to Fig. 3, it will be noted that sets of the track sections 87 to 92 occur in pairs along the length of travel of the conveyor 66. The right hand set of each pair is arranged to cause the belt to move toward the right, and the right hand hopper 74 delivers material to that beater tank over which it may be positioned. A slight movement of the shuttle travel toward the left is however sufficient to cause interruption of the contacts between the right hand set of tracks and the trolley wheels, and instead, a left hand set becomes active. The connections are now such as to 60 cause the belt to travel toward the left, and 65

to discharge material from the left hand hopper to whichever one of the left beaters it may be positioned over. Further movement of the shuttle travel toward the left will cause the right hand hopper 74 to be active again, but this time with respect to a beater tank situated to the left of that first mentioned. Of course the tracks 87 to 92 are so disposed with respect to the beater tanks that the connections are completed thereby only 75 when the corresponding hopper 74 or 75 is in proper position over the tank to be supplied. From this description of the shuttle mechanism, it is seen that a very simple and efficient distributor mechanism is provided 80 thereby.

Before proceeding with the detailed description of the control circuits, whereby the proper sequence of operation of the various mechanisms is assured, attention is again directed to Fig. 1. It is to be noted that the scale conveyor motors 29, 30 and the feeder motors 35, 36 are each equipped with solenoid brakes 99, 100, which are energized to release the brakes whenever the respective motors are 90 energized. This is a well-known expedient to prevent overrunning, and since the operating solenoids are simply connected in parallel to the respective motor leads, in the wiring diagrams of Figs. 9, 10 and 11 they have been 95 merged with the motors. In this way separate representation of the brakes is avoided.

The control system which we shall now describe is so arranged that the various elements, such as the feeders, blowers, and shredders, are dependent upon each other, so that it is impossible for example to operate the blowers or the feeders until the shuttle conveyor belt 66 is in motion. Other precautionary control circuits are included which will be described later on.

In order to inform the operator at the control panel 21 which beater is to be supplied, and also to keep him informed of the position of the conveyor belt 66, so that he may continue to operate the shuttle travel motor 82 until the hopper 74 or 75 is in proper position for discharging its load, we provide a signaling system, including two signal transmitting switches illustrated in Figs. 6, 7 and 8. These 115 switches are arranged to be operated by the attendant in the beater room, and may be located one near each end of this room. Each switch comprises a box 102 in which the rod 103 is slidable, as by the aid of the handle 104 120 fixed to its ends. On each side of the box 102 are a plurality of contact studs 105 supported on suitable insulating boards, and arranged in groups of three, forming triangles, as plainly indicated in Fig. 8. The rod 103 carries a pair of contact pieces 106 and 107 on a yoke 108. The rod 103 may be operated to connect any set of three contacts 105 together, by first properly positioning the rod 103 axially, and then rotating it either to the right or 125 130

left. In order to make sure that only sets of three contacts can be connected together at one time, and no other improper aggregation of contacts, we provide a pair of guide plates 109 (Fig. 7) in which notches 110 are cut to permit the entry of the wedge shaped extensions 111 carried by the yoke 108. These notches as shown in Fig. 8 are so positioned with respect to the contacts 105 that they permit rotation of rod 103 only when the contact pieces 106, 107 are in alinement with a set of these contacts. In intermediate axial positions, as for example that illustrated in Fig. 8, the rod 103 would have its rotation stopped by the engagement of the extensions 111 with the guides 109, before any contacts can be closed.

In Fig. 9, the transmitting switches are shown diagrammatically, and are marked "Beater room signal switches". In order that the beater room attendant may verify his signals there are beater room telltale lights 112 and 113, which operate behind transparent signs 114 (Fig. 6). These signs are all appropriately supported in a supplementary box 115, there being one such box for each of the switches. On the control panel 21, similar signs 116 and 117 are provided, behind which are the control panel telltale lights 118 and 119 (Fig. 10).

The beaters 58, 59, 60, etc., being in the present instance divided into two units of six each, there is therefore a transmitting switch for each unit. Now let us suppose that the beater room attendant desires to transmit a signal to the control panel operator that he is to furnish material to beater No. 1 of the left hand unit. He manipulates rod 103 so as to connect the extreme lower left hand set of three contacts 105, of the left hand switch, as indicated in Fig. 9. For this position, two lights will be illuminated behind signs 114 in the beater room telltale box 115, and also behind the signs in the left hand group 117 on panel 21, so that the word "Furnish" and numeral "1" will be illuminated in both places on the left hand telltales. The circuits for these lights will now be traced.

The leads 120, 121 connect to an appropriate source, and serve to supply electrical energy to the signal system. In the present instance this source is a transformer 122 (Fig. 10) which is supplied from one phase of the three phase mains 123. The lead 120 goes to a junction point 124; thence the circuit extends to the contact piece 106. The circuit from this point for one of the transmitter telltale lamps 113 proceeds through junction point 125, right hand lamp 113, illuminating the sign "Furnish" at the transmitter, thence by lead 126 to line 121. At the same time, the control panel telltale lamp 119 illuminating the sign "Furnish" at the panel 21 is energized, through this circuit, from junction 125, lead 127, to one of the

lamps 119, then by lead 128 back to the main 121. From contact piece 106 two other circuits may be traced through a lamp 112 and a lamp 118 that illuminate the signs "1" at both the transmitter and the panel 21. One of these circuits extends from contact piece 106, through lead 129, junction point 130, extreme left hand lamp 112, back to lead 121 by way of lead 126. Another circuit may be traced from contact piece 106 to point 130, the sixth lamp 118 from the right at the sign 117 on panel 21, then by way of lead 128 to the lead 121. By shifting the contact piece 106 or 107 to any desired set of contacts 105, any other set of signal lamps 113, 112, 118 and 119 may be lit, to produce the proper indication.

In the diagram of the transmitting switches of Fig. 9, the lower six sets of contacts 105, which represent the contacts supported on one side of the box 102 (Fig. 7) control the circuit for the right hand lamps of the groups 113 and 119, while the upper set of contacts 105, which represent those supported on the other side of box 102, control the circuits for the left hand lamps of these groups 113 and 119. Thus by rotating shaft 103 between its two positions, it is possible to change the indication from "Furnish" to "Next"; this latter signal is produced at the transmission end by energization of left hand lamp 113, and at the panel 21 by energization of left hand lamp 119. Mere rotation of rod 103 however does not change the energization of the selected light 112 or 118, due to the use of the jumper connections 131 which tie in corresponding contacts in the upper and lower sets.

The signal "Next" of course simply means that after the completion of the operation of supplying material to the particular beater, the operator is to proceed to supply any other desired beater. In this way, the operator is apprised some time in advance of the next set of operations he must perform, and there can be no delay incident to the transmission of signals.

Circuits for the other signal lamps in groups 112 and 118 are entirely similar to those already traced for the left hand lamp of each group, and become active when contact piece 106 or 107 is moved to make connection with the proper set of contacts 105.

The transmitting switch shown to the right of that already described, is located near the right hand beater unit, and serves to produce indications at telltale sign 116 on the panel 21. In the position shown, the signal "Furnish 6" is transmitted. The circuits for the left hand lamp of group 118 and 119 are completed, causing this indication at the transmitter and at the panel 21. For lamp 113, the circuit is as follows:—from main 120, contact piece 107, junction 132, left hand lamp 113, lead 133 back to main 121. The

circuit for lamp 119 at the panel 21 is as follows:—from main 120, contact piece 107, junction 132, lead 134, lamp 119, and lead 128 back to main 121. These circuits cause 5 illumination of signs "Furnish" for the right hand unit.

Other circuits, illuminating signs "6" are also completed. The left hand lamp 112 at the transmitter switch is energized for this 10 purpose as follows:—from main 120, contact piece 107, lead 135, left hand lamp 112, lead 133, back to main 121. The left hand lamp 118 of the sign 116 is also energized as follows:—from main 120, contact piece 107, 15 leads 135 and 136, left hand lamp 118, and lead 128 back to main 121.

From these examples of signaling circuits which have been traced, it is possible readily to deduce the corresponding circuits for 20 any of the other lamps as the rod 103 of the transmitting switches are manipulated. The telltale lights 112 and 113 serve as guides for the attendant at the beaters, not only to indicate to him what signal is being transmitted, but also just how far rod 103 is to 25 be moved to produce any other desired signal.

On the indicators or signs 116 and 117 at the control panel 21, there are rows of numerals beneath the signals just mentioned, which 30 are arranged to indicate the operative position of the shuttle belt frame 70. The indications are produced by the coaction of the trolley wheels 83 with the short tracks 90 and 91, located in the path of travel of the shuttle 35 belt frame 70. For example, this frame is indicated diagrammatically in Fig. 11 at the upper left hand corner as being in proper position to supply beater 6 of the right hand unit. The circuit energizing a lamp 137 to 40 illuminate lower numeral 6 of sign 116 is correspondingly completed, as follows:— from main 120, to wire 138, track 91, wheels 83, track 90, wire 139, lamp 137, and lead 128 back to main 121. Registry of the trolley 45 wheels 83 carried by frame 70 with succeeding sets of tracks will cause illumination of the proper numeral of the lower rows of both signs 116 and 117. For example, the next set of tracks to the right, on Fig. 11, control the lamp 140, showing that the conveyor is 50 operative to supply beater 1 of the left hand unit. This is the correct indication, for the tracks 87, 88 and 89 provide for a reversal of the conveyor motor 73 as compared with its rotation 55 in the position actually shown, and it is the left hand hopper 75 that is used to discharge the material. As the shuttle travel motor 82 is actuated to move the frame 70, successive lamps will be lit back of the lower row 60 of numerals in signs 116 and 117, and the operator at panel 21 will thus be kept informed of the operative position of the conveyor frame 70.

As an additional safeguard, we prefer to 65 supply another signaling device that is re-

sponsive to the movement of the frame 70. This is useful in order to ensure that the operator at panel 21 will not set into operation any unit of mechanism until after the conveyor frame is at rest. This signaling device 70 includes a "blinker" light 141 located between the two signs 116 and 117, and illustrated diagrammatically on Fig. 10. This light flashes on and off while the frame 70 is moving, and while trolley wheels 83 engage the tracks 90, 75 91 and 92. This "blinking" circuit when these conditions are fulfilled may be traced as follows:—from main 120, lead 138, track 91, trolley wheel 83, a commutator 142, running in unison with the frame, lower wheel 83, track 92, connections 143 and 144, lamp 141, lead 128, back to main 121. While the frame 70 is travelling, the commutator 142 is rotating, and causes alternate opening and closing 80 of the circuit just traced, with consequent "blinking" of light 142. This blinking is an indication to the control panel operator, and he is to take care not to set any interfering apparatus into motion until the lamp 141 is permanently dark or permanently lit. 90

The signaling circuits have now all been described. From the indications thereby produced, the control panel operator can take the proper steps to supply the desired beater or mill. While these beaters are continuously 95 in operation, the blowers, shredders, scale conveyors, shuttle belt conveyor and shuttle travel winch are under the control of this operator, and are usually placed in operation only intermittently and as required. The control circuits of these elements are so arranged that such sequence of operation may be performed which ensures against choking any of the conveyors or chutes with the material, and against unloading while the conveyor 66 is not 100 in proper position to discharge the material. 105

The first step taken by the operator is to move the conveyor frame 70 to the desired position. This he effects by the aid of the reversing motor 82, the connections for which 110 are controlled by the lever switch 144* (Figs. 5 and 10). If he desires movement of the shuttle belt to the left, he moves the handle for this switch to the left, and the three pole switch 145 is closed, due to the energization of solenoid 146. The circuit for this coil may be traced as follows:—from the control main 147, which connects to one terminal of the supply transformer 122, lead 148, switch 144*, lead 149, solenoid 146, lead 150, to a left hand shuttle travel limit switch 151, lead 152, to lead 159 forming the other control main, and connecting to the other terminal of transformer 122. The limit switch 151 is arranged to be opened by the shuttle frame 115 70 in case it exceeds the desired limit of its travel. It comprises a lever 153, one extremity of which is in the path of travel of the frame 70. The lower switch 145 being now closed, the circuit for motor 82 is completed, 120 125 130

from mains 123, switch 154, leads 155, switch 145, leads 156 to the motor 82. The source of supply in this instance is shown as three phase, but of course any other type, either alternating or direct current could be used. The motor 82 may advantageously be of the squirrel cage induction type. If it be desired to move the frame 70 to the right, the switch 144^a is moved to the right, and this movement causes the solenoid 157 to be energized, while solenoid 146 is deenergized. This solenoid 157 pulls the upper switch 158 to closed position, while gravity or a spring returns the lower switch 145 to open position. The circuit for solenoid 157 may be traced as follows:—from main 147, lead 148, switch 144^a, lead 160, solenoid 157, lead 161, shuttle travel limit switch 162, lead 152, back to the other main 159. The limit switch 162 is entirely similar to switch 151, except that it is placed in the path of travel of the shuttle frame 70 at its right hand end, so as to cause the frame to open the switch and prevent overrunning. The closure of the upper main switch 158 by the energization of solenoid 157 causes the motor 83 to be run in an opposite direction, due to the arrangement of the phase leads 163 connected by the switch 158 between the leads 156 supplying the motor, and the supply leads 123. After the shuttle frame 70 has moved into proper operative position with respect to the desired beater, as indicated on one of the signs 116, 117, the operator returns switch 144^a to central position; in this position, neither of the solenoids 146, 157 is energized, and therefore both switches 145 and 158 are open, and the corresponding motor circuit is dead.

Either of the hoppers 74, 75 being now in proper position to discharge to a selected beater, the shuttle conveyor 66 may now be operated by the energization of motor 73. The control of this motor at panel 21 is effected by a pair of push buttons 164 and 165 which are resiliently urged as by springs to the positions shown in Fig. 10, but may be manually depressed to start and stop the motor 73. However, starting of this motor cannot be effected until the shuttle travel switch 144^a is in central position, which corresponds to inactive condition of the shuttle travel motor 82. When this condition is fulfilled, depression of button 164 for a short time serves to energize the switch operating solenoid 166, closing switch 167. The circuit may be traced as follows:—main 159, lead 168, push button 164 in depressed position, push button 165 in free position, lead 169, solenoid 166, overload contacts 170, lead 171, switch 144^a, and lead 148 to main 147. The overload contacts 170 serve to interrupt this solenoid circuit whenever the load on the motor 73 becomes dangerously high. As soon as this circuit is completed, switch 167 closes, and completes the circuit for the motor

73 from mains 123 to leads 172, tracks 87, 88, 89, wheels 83 to motor 73. The particular connection between leads 172 and tracks 87, 88, 89, determine the direction of rotation of motor 73. For instance on Fig. 11, 70 the tracks 87, 88 and 89 at the extreme left hand position are connected respectively with the lower, middle, and upper lead 172, whereas the next set of tracks are connected in reverse order. In this way a reversal of the 75 motor 73 is secured as it is moved from one position to the next, and there is a corresponding alternation in the activity of hoppers 74 and 75.

As soon as the motor 73 is in operation, the 80 push button 164 may be released, and it will take the position shown in the diagram. However, there is a holding circuit for the coil 166, closed by the closing of contacts 173, operated also by solenoid 166. This closing 85 circuit may be traced as follows:—from main 147, to lead 148, switch 144^a when in open position, lead 171, overload contacts 170, solenoid 166, lead 169, “stop” push button 165, lead 174, contacts 173, and lead 175 back to 90 the other main 159. This holding circuit stays completed until “stop” button 165 is pressed, when the switch 167 is released, and the apparatus returns to the position shown on the drawings. 95

As soon as the shuttle belt is in operation due to rotation of motor 73, the machinery for supplying material thereto may be started. In order to ensure that the units of machinery cannot be operated except when the belt 100 66 is running, we provide a switch 176 (Fig. 11) which is closed only when the switch 167 is closed. This switch controls the circuits for the blower motors 55, 56, as well as the feeder motors 35 and 36. The switch 176 is 105 operated by a solenoid 177, the circuit for which may be traced as follows:—from main 147, lead 178, solenoid 177, lead 179, contacts 173, and lead 175 back to the other main 159. This circuit is operative of course only when 110 contacts 173 are closed, which in turn depend upon the closure of switch 167.

The switch 176 has a pair of levers, each of which controls the circuits for one set of feeder and blower. The control circuit for 115 blower motor 55 (shown in the diagram of Fig. 9 at the extreme right and labelled “Blower No. 1”), is operated by the start and stop push buttons 180 and 181 (Fig. 10). To start the motor, button 180 is depressed and held there for a short time, sufficient to cause energization of holding circuits. This starting circuit may be traced as follows:—from main 159, to lead 182, a solenoid 183 serving to set in operation an automatic starter 184, lead 185, button 180, button 181, lead 186, right hand pole of switch 176, lead 187, overload contacts 188 for the motor 55, back to the other main 147. It is thus seen that this 120 control circuit can be energized only when 125 130

switch 176 is closed. The energization of solenoid 183 causes the automatic starter to bring the motor 55 to speed, and is necessary because of the large size of motor used for the blower. The particular details and circuits for this starter are not shown, since they are standard and may be of various forms.

As soon as this starting circuit is energized, the solenoid 183 also closes the "holding" contacts 189, whereby even after the starting button 180 is released, the solenoid is still active. This holding circuit may be traced as follows:—from main 159 to lead 182, coil 183, contacts 189, lead 190, stop button 181, lead 186, switch 176, lead 187, overload contacts 188, and back to the other main 147. By pushing the button 181, this circuit can be interrupted, and the coil 183 deenergized, permitting the automatic starter 184 to return to its open position and stopping operation of motor 55.

Once the conveyor belt motor 73 is in operation, of course either or both of the blower motors 55, 56 may be started. The control circuits for motor 55 have already been described, and those for blower motor 56, (shown at the extreme left of Fig. 11) are entirely similar. They will therefore be indicated only in a cursory fashion. The "start" and "stop" buttons 191 and 192 control the operation of automatic starter 193. For starting, the circuits are as follows:—main 147, overload contacts 194, switch 176, lead 195, button 192, button 191, lead 197, coil 198, and thence back to the other main 159. The holding circuit, after button 191 is released, is as follows:—main 147, overload contacts 194, switch 176, lead 195, button 192, lead 196, holding contacts 199, coil 198, and back to the other main 159.

The blowers being now in operation (or one of them, in case a relatively small amount of material is needed), the shredders 43 and 44 may be started, since they are the next links in the chain of the mechanism. The shredder motors 47 and 48 are controlled by push buttons, similar to those used for the blower motors. However, since the operation of the shredders does not in itself give rise to accumulation of material or dangerous conditions of any point, there is no necessity for causing the control for the shredders to be dependent upon the operation of any of the other mechanisms. In other words, elements such as the conveyors, feeders, and blowers, must cooperate to bring material to the shredders and to take it away, and must therefore be properly interlocked for this purpose; while the shredders themselves are independent mechanisms which may be either idling, when the conveyor chain of mechanism is idle, or doing useful work when the conveyor chain is active and carrying material to and from the shredders.

The control of shredder motor 47 may now be described. Since this motor is of large capacity, an automatic starter 200 is provided therefor, having an operating solenoid 201. The starting and stopping is effected from a pair of push buttons 202 and 203. The starting circuit may be traced as follows:—main 147, lead 204, overload contacts 205, lead 206, buttons 203 and 202, lead 207, coil 201, and lead 208 back to the other main 159. As soon as this circuit is completed, the holding contacts 209 are closed, and a holding circuit is active, independent of the starting button 202, which may now be released without stopping the motor. This holding circuit may be traced as follows:—main 147, lead 204, overload contacts 205, lead 206, button 203, lead 210, contacts 209, coil 201, and lead 208 back to the other main 159. To stop the motor 47, the push button 203 is depressed, and this holding circuit interrupted. As before, the overload contacts 205 ensure against dangerous overloading of any of the phases of the motor 47, and serve to interrupt this holding circuit when that occurs. The motor 47 is supplied through a main switch 211 and the automatic starter 200, which is active to supply the motor only when coil 201 is energized.

The control circuits for shredder motor 48 on Fig. 11 are entirely similar to those just described in connection with motor 47. The starting circuit may be traced as follows:—from main 147, lead 213, overload contacts 212, lead 214, stop button 215, start button 216, lead 217, starting coil 218, and lead 219 back to the other main 159. After the holding contacts 220 are closed by coil 218, the holding circuit is completed as follows:—from main 147, lead 213, overload contacts 212, lead 214, stop button 215, lead 221, holding contacts 220, coil 218, and lead 219 back to the other main 159.

Although it is possible to start the two shredder motors 47 and 48 independently of the other units, the operation of these motors is an essential before the respective feeder motors 35 and 36 can be started. Each of the feeder motor controls is in addition so arranged that the respective shredder motor must be operative, but without undue load, and the corresponding blower motor must also be operative. In case the shredder motors are too heavily loaded, the feeder motors become deenergized, but are automatically energized when the load becomes normal. This control ensures against choking the shredders unduly with raw material supplied by the feeders. The various controls for the feeders will now be described.

Considering first the feeder motor 35, it is seen in Fig. 9 that it may be supplied through manually operated switch 222 and the solenoid coil operated switch 223, from the mains 123. Overload contacts 224 are provided to

ensure against injurious load conditions. The circuit for the coil 225 that operates the switch 223 is controlled at panel 21 by the push button control 226 which is of the non-return type; that is, when the button is depressed to start the motor, it stays in that position until it is moved outwardly by the aid of another button. This is necessary in view of the nature of the controls, and is entirely similar to the usual type of wall switches controlling lamps in residences. When this button 226 is depressed, the circuit for coil 225 is completed, provided the corresponding shredder motor 47 is operating at normal load, and the corresponding blower motor 55 is operating. The circuit for coil 225, when these conditions are fulfilled, may be traced as follows:—from main 159, lead 227, button 226, lead 228, an emergency button 229 (located at the shredder and when depressed serving to interrupt the circuit and provided for the operator at that point as an extra safeguard against dangerous conditions), lead 230, contacts 231 (operated by solenoid 232 energized from mains 159, 147, when contacts 233 are closed; operation of these contacts being responsive to conditions in the current coil 234 located in one of the leads of shredder motor 47, whereby when the shredder load is greater than a desired maximum, the coil 234 carries a heavy enough current to cause movement of the upper contact disc away from the stationary contacts), lead 235, contacts 236, coil 225, overload contacts 224, lead 237, holding contacts 189 on the corresponding blower motor 55, which are closed only when that motor is in operation, lead 190, stop button 181 of blower motor 55, lead 186, switch 176, lead 187, overload contacts 188 of blower motor 55, and back to the other main 147. The contacts 236 in this circuit are controlled so as to close only when the shredder motor 47 is in operation. For this purpose the coil 238 is provided which is arranged to be placed in parallel to the operating coil 201 of the automatic starter 200, by the aid of another set of contacts 239, operated by coil 240. This latter coil is shown as having its circuit controlled from the starter 201, so that this starter must be in full running position before coil 240 is energized. In this way it is assured that shredder motor 47 is in full operation before the feeder motor 35 can operate. To stop the feeder, it is merely necessary to manipulate the button 226 to open position.

The feeder control circuit as traced is such that it is operative only in response to certain predetermined conditions of the machinery associated therewith. Contacts 236 tie up the feeder with the shredder; contacts 231 may be opened and closed alternately as the load varies on shredder motor 47, causing intermittent operation of feeder 33; contacts 189 on the blower motor starter 184 make it

certain that this motor must be in operation, and the completion of the circuit through the switch 176 ensures a direct dependance of the feeder motor upon the operation of the shuttle belt 66. All these safeguards are taken to make the system as safe as can reasonably be expected, since serious and irreparable damage would undoubtedly occur upon improper operation of the feeder belts.

The corresponding controls for the other feeder motor 36 may be somewhat cursorily traced, since the operations of both are identical. Of course in this case the feeder motor 36 is dependent upon the operative conditions of its associated shredder motor 48 and blower motor 56. This feeder motor 36 is likewise controlled by a manually operated switch 241 and a switch 242 operated by solenoid 243. Overload contacts 244 are also provided. When the control push button 245 at the panel 21 is pushed, and the shredder and blower motors 48 and 56 are in normal operation, the solenoid 243 is energized through the following circuit:—from main 159, lead 246, button 245, lead 247, emergency button 248, lead 249, contacts 250 (closed only when starter for motor 48 is in full on position), lead 251, contacts 252 (closed only when shredder motor 48 is operating below a predetermined maximum load), coil 243, overload contacts 244, lead 253, holding contacts 199 on blower motor starter 193, lead 196, blower motor stop button 192, lead 195, switch 176, overload contacts 194 on motor control 56, back to main 147.

Since conveyors 31 and 32 are geared respectively to feeders 33 and 34, these conveyors are now also in operation. The scales 23 and 24 may now be used to weigh out the raw material, and the corresponding conveyors 27, 28 operated to supply the feeders. The motors 29 and 30 operating these conveyors are reversible, so that either scale may supply either feeder. The control circuits however are so arranged that the motors 29 and 30 can operate only in a direction that causes the conveyors 27, 28 to discharge to a moving feeder 33 or 34.

Thus considering first the scale conveyor motor 29, shown at the right of Fig. 10, it is seen that the circuit for supplying the motor with electrical energy includes the manually operated switch 254, and either one of the two solenoid operated switches 255 or 256. When coil 257 is energized, the switch 255 is closed, and the motor operates in the proper direction to supply conveyor 33 with material; if on the other hand, coil 258 is energized, then feeder 34 is supplied from scale 23. The operation is controlled from the panel 21 by a lever switch 259, which may be turned in either direction to control either of the coils 257 or 258. Assuming that feeder 33 is in operation, throwing the switch 259 to the left will energize coil 257, and the motor

29 will rotate to drive conveyor 27 toward feeder 33. The circuit for coil 257 is completed as follows:—from main 147, lead 260, switch 259, lead 261, coil 257, lead 262, contacts 263 (closed only when switch 223, controlling operation of feeder 33, is closed), and lead 264 back to the other main 159. From consideration of this circuit it is seen that the coil 257 can be energized to cause 10 movement of belt 27 toward feeder 33 only when this feeder is moving.

If lever switch 259 be turned to the right, the motor 29 will be energized to drive the conveyor belt 27 toward feeder 34, but only 15 on condition that said feeder is moving. The circuit for coil 258, which accomplishes this result, may be traced as follows:—from main 147, lead 260, switch 259, lead 265, coil 258, lead 266, contacts 267 (closed only when 20 switch 242, controlling operation of feeder 34, is closed), and lead 268 back to the other main 159.

The other scale conveyor motor 30 is similarly controlled by the lever switch 269. The 25 supply circuit for this motor includes the manually operated switch 270, and either of the two coil operated switches 271, 272. When switch 271 is closed due to energization of coil 273, the motor 30 operates to supply 30 feeder 33; on the other hand, energization of coil 274 will close switch 272 and cause the motor 30 to rotate in the opposite direction to supply feeder 34. When lever switch 269 is thrown to the left, the circuit for coil 273 35 is completed as follows:—from main 147, lead 275, switch 269, lead 276, coil 273, lead 262, contacts 263 on switch 223, and lead 264 back to the other main 159. Contacts 262 as before insure operation of feeder 33 before 40 the motor 30 can operate to supply material thereto. In a similar manner, throwing switch 269 to the right energizes coil 274 and causes motor 30 to operate in the reverse direction. The circuit may be traced as follows:—from main 147 to lead 275, lever switch 269, lead 277, coil 274, lead 278, lead 266, contacts 267 on switch 242, and lead 268 back to the other main 159.

The control circuits have now been fully 50 described. The wires and leads necessary for the circuits may be housed in conduits 279 running at the back of the panel 21. The main switchboard for the main power lines and the power switches may be located as at 55 101 in one corner of the beater room shown in Fig. 3. A bell or other type of signal may be provided for use by the panel operator, and the control button for such a signal is shown at 280 on Fig. 5. By the aid of this signal, 60 the operator may communicate in any desired manner with any of the attendants and operators located at a distance from the board 21.

A brief summary of the operation of the 65 plant may now be described. Let it be as-

sumed that the attendant in the beater room desires to have material furnished to the left beater No. 4. He manipulates the rod 103 of the corresponding transmitter switch, so as to transmit the signal "Furnish 4" which 70 appears illuminated on the left hand sign 117 at the panel 21. The operator at the panel 21 then moves lever 144 to operate the shuttle travel motor 82. The succession of lighted numerals on signs 116 and 117 will indicate 75 in what direction the shuttle conveyor frame 70 is moving, and he is guided accordingly in his operation of switch 144. As soon as the numeral 4 of the lower row, lights on sign 117, he brings his lever 144 to central position. 80 The shuttle belt 66 may now be operated, and he accomplishes this by pressing button 164. The direction of travel is automatically correctly determined by the tracks 87, 88 and 89, and the wheels 83. After the shuttle belt 85 motor is in operation, contacts 173 close on switch mechanism 167, and they energize solenoid 177 for closing switch 176. This switch being closed, either of the blowers may be started by pressing button 180 or 191. In 90 case the beater is in need of only a small amount of material, only one blower would be placed in operation. As soon as the blower is in operation, the corresponding shredder may be started, as by pushing button 202. 95 Operation of this shredder causes contacts 231 and 236 to close, and the operator can start feeder motor 35 by manipulating button 226. The contacts 263 are closed in response to the 100 operation of feeder motor 35, and this closure permits the operator to move the material from either scale 23 or 24 to feeder 33, by operation of either of the switches 259 or 269. But before starting the scale motors, the operator first weights out the desired material 105 on the scale. In case a "Next" signal has been transmitted, and after he has completed these controls, he can weight out on the other scale, the material needed for the next beater to be supplied. 110

The material weighed out on the first scale is carried by feeder 33 to shredder 43, whence it is discharged to the blower 51. This blower carries it to the cyclone 65, which delivers it to the moving belt 66, and the left hand hopper 75 finally transfers it into the left hand beater No. 4. The next batch of material may be started on its way; the operator brings his shuttle travel switch 144 to the right or left to start the shuttle travel motor 82 in the proper direction, so as to position the shuttle conveyor properly with respect to the next beater to be supplied. Movement of the lever switch 144 away from central position, causes deenergization of the shuttle belt motor 73 as described; this in turn causes separation of contacts 173, and consequent interruption of the holding circuit for the blower motor 55. The feeder 33 is rendered inactive, 120 also, due to the opening of the holding con- 125

tacts 189 on the blower motor, and neither scale motor can be started, due to the opening of the feeder motor circuits. The shredder 43 however, may remain operative and 5 ready to operate on the material as soon as the chain of mechanism is operative to convey material to and from it. However, the shuttle travel motor 82 must first be brought to rest by bringing switch lever 144 to central position, before this chain of mechanism can be rendered operative. Furthermore, the shuttle frame 70 must be brought to rest in a position where its trolley wheels 83 engage the tracks 87, 88 and 89; otherwise the 15 conveyor motor 73 could not be operated, nor any of the other units in the chain of mechanism. The tracks 87, 88 and 89 thus insure by their position against operation of the mechanism unless either hopper 74 or 75 is 20 in proper position to discharge its load.

The entire system as described may thus be brought into harmonious operation by comparatively few attendants. The provision of the shredding operation renders the plant 25 more efficient, the paper production being faster since the operation of beating can be shortened. Due to the provision of the scales, accurate weighing of the raw material is possible, and uniformity of the product is assured. 30

We claim:

1. In combination, a pair of conveyor mechanisms arranged adjacent each other and to carry material, a conveyor belt between the 35 mechanisms, and means for driving said belt in either direction to supply either of the mechanisms with material.

2. In combination, a conveyor mechanism, a measuring device and a conveyor belt having its upper reach arranged to support the measured material and to move said material to the conveyor mechanism. 40

3. In combination, a pair of conveyor mechanisms arranged adjacent each other and to carry material, a measuring device, a conveyor belt having its upper reach arranged to support the measured material, and extending between the mechanisms, and means for selectively moving said conveyor belt to supply either mechanism with material. 45

4. In combination, a pair of conveyor mechanism, means common to both mechanisms for supplying either of said mechanisms with material to be conveyed, and 55 means for insuring that said supply means can be operated to supply material to either mechanism only when that mechanism is in operation.

5. In combination, a conveyor mechanism, 60 independently driven means for supplying said mechanism with material to be conveyed, and means for insuring that said supply means can be operated to supply material to the mechanism only when said mechanism is 65 in operation.

6. In combination, a pair of conveyor mechanisms, a conveyor belt arranged between said mechanisms, means for moving said belt in either direction, whereby either mechanism may be supplied with material 70 to be conveyed, and means insuring that said belt can be operated in a desired direction only when the mechanism to be supplied thereby is in operation.

7. In combination, a pair of conveyor 75 mechanisms, a pair of machines, one associated with each mechanism, for changing the state of material conveyed to it by the mechanism, means for supplying either of said mechanisms with material to be conveyed, and means for insuring that said supply means can be operated to supply material to a mechanism only when the load on the machine to which the material is to be conveyed by said mechanism, is below a predetermined 80 maximum. 85

8. In combination, a conveyor mechanism, a machine associated with said mechanism, for changing the state of material conveyed to it by the mechanism, means for supplying said 90 mechanism with material to be conveyed, and means for insuring that said supply means can be operated to supply material to the mechanism only when the load on the machine is below a predetermined maximum. 95

9. In combination, a pair of conveyor mechanisms, a conveyor belt arranged between said mechanisms, means for moving said belt in either direction, whereby either mechanism may be supplied with material to be conveyed, a pair of machines, one associated with each mechanism, for changing the state of the material conveyed to it, and means insuring that said belt can be operated in a desired direction only when the load on the machine to be supplied with material thereby, is below a predetermined maximum. 100

10. In paper making machinery, a pair of conveyor mechanisms, a pair of shredders for shredding raw material brought to them by the conveyor mechanisms, there being a shredder associated with each mechanism, means for supplying either of said mechanisms with material to be conveyed, and means for insuring that said supply means can be operated to supply material to the mechanism only when the shredder is operating below a predetermined maximum load. 110 115

11. In paper making machinery, a conveyor mechanism, a shredder associated with the mechanism for shredding raw material brought to it by the mechanism, and means for insuring that said mechanism can be operated only when the shredder is operating below a predetermined maximum load. 120 125

12. In paper making machinery, a conveyor mechanism, a shredder associated with the mechanism for shredding raw material brought to it by the mechanism, means for supplying said mechanism with material to 130

be conveyed, and means for insuring that said supply means can be operated to supply material to the mechanism only when the shredder is operating below a predetermined maximum load.

13. In paper making machinery, a pair of conveyor mechanisms, a conveyor belt arranged between said mechanisms, means for moving said belt in either direction, whereby either mechanism may be supplied with material to be conveyed, a pair of shredders, one associated with each mechanism, for shredding raw material brought to it by the mechanism, and means insuring that said belt can be operated in desired direction only when the shredder to be supplied with material thereby is operating below a predetermined maximum load.

14. In paper making machinery, a shredder for shredding raw material of assorted sizes into particles small enough to permit their use for pulp, a conveyor mechanism for supplying said shredder with the raw material, and means operating on the material in the conveyor for regulating the depth of the material carried thereon, whereby the rate of feed is prevented from varying greatly.

15. In paper making machinery, a shredder for shredding raw material of assorted sizes into particles small enough to permit their use for pulp, a conveyor mechanism for supplying said shredder with the raw material, and a wheel having paddles operating on the material in the conveyor to regulate the depth of the material carried thereon, whereby the rate of feed is prevented from varying greatly.

16. In paper making machinery, a shredder, conveyor mechanism for supplying raw material to the shredder, independently driven conveyor mechanism for transporting the shredded material from the shredder, and means insuring that the supply conveyor can be operated only when the other conveyor is in operation.

17. In paper making machinery, a shredder, a conveyor mechanism for supplying raw material to the shredder, a conveyor mechanism for transporting material from the shredder, a movable distributing mechanism associated with said latter conveyor, and means insuring that said distributing mechanism and its associated conveyor are in operation before the supplying conveyor can be placed in operation.

18. In paper making machinery, a shredder, means for supplying material to the shredder, means for distributing the material after it leaves the shredder, a common controller for the shredder, supplying and distributing means, and means adjacent the controller for indicating the position of the distributor.

19. In paper making machinery, a shred-

der, independently driven means for feeding material to the shredder, means for transporting the material from the shredder, and means insuring that the feeding means will be operative only when the transporting means is active.

20. In paper making machinery, a shredder, means for feeding material to the shredder, and means insuring that the feeding means will be operating only when the shredder is active.

21. In paper making machinery, a shredder, means for feeding material to the shredder, a motor for driving the shredder, and means responsive to load conditions on the motor for controlling the feeding means.

22. In paper making machinery, a shredder, a conveyor for feeding the shredder, an electric motor for driving the conveyor, an electric motor for driving the shredder, and means responsive to the load conditions on the shredder motor for controlling the circuit of the conveyor motor.

23. In paper making machinery, a pair of shredders, conveyors associated with each shredder for feeding material thereto, a distributor associated with both shredders for carrying away the material from the shredders to any one of several points, and means responsive to the setting of said distributor in operation to supply material to one of these points, for permitting the feeder conveyors to supply material to the shredders.

24. In paper making machinery, a pair of shredders, conveyors associated with each shredder for feeding material thereto, a distributor associated with both shredders for carrying away the material from the shredders to any one of several points, and means for insuring that either of the feeder conveyors can be operated only after the distributor is in proper position to discharge material to one of said points.

25. In paper making machinery, a shredder, means for feeding material to the shredder, means for transporting the material from the shredder, and means controlling the operation of the feeding means, said controlling means being responsive to the operative condition of both the shredder and the transporting means.

26. In paper making machinery, a shredder, a feeder for supplying the shredder with material, a motor for driving said feeder, a mechanism for carrying away the material from the shredder, and a controller for the motor responsive to load conditions at the shredder and also to the operative condition of the mechanism.

In testimony whereof, we have hereunto set our hands.

LELAND S. ROSENER.
DAVID H. PATTERSON, JR.
